WILLIAM C. CORYELL, OF YOUNGSTOWN, OHIO.

REINFORCING-BAR FOR CONCRETE AND SIMILAR STRUCTURES.

1,076,192.

Specification of Letters Patent.

Patented Oct. 21, 1913.

Application filed May 22, 1908. Serial No. 434,371.

To all whom it may concern:

Be it known that I, WILLIAM C. CORYELL, a citizen of the United States, residing at Youngstown, county of Mahoning, State of Ohio, have invented certain new and useful Improvements in Reinforcing-Bars for Concrete and Similar Structures, of which the following is a specification.

The present invention relates to reinforcing bars of metal for use in concrete and similar constructions, and the general object of the invention is to produce a bar of this kind which may be economically manufactured and which will effectively and efficiently perform its functions in the constructions in which it is employed. To this end, I have provided a bar having a central body and one or more sets of obliquely arranged transverse ribs. The body of the bar conforms generally to some regular standard shape, and the ribs are short, preferably extending not more than half way around the body of the bar, and in themselves vary in cross-sectional area from a maximum near their centers to a minimum at their ends. The bar is of approximately uniform cross-sectional area throughout, the area of the body bearing a constant ratio to the aggregate area of the ribs, and the parts of the bar are preferably arranged so as to prevent its twisting under the forces to which it is subjected when in service. This may be accomplished by giving all the ribs the same direction of obliquity, forming the body of the bar with a non-circular cross-section and then twisting the bar as a whole in a direction opposite to that of the obliquity of the ribs; or it may be done by pairing each rib with another having an opposite angle of obliquity. Obviously, in practising my invention, the section of the body of the bar may be variously formed, and the ribs may be distributed over the body according to many different arrangements and such distribution may be combined with a twist in the bar or not, as expediency or design may dictate.

The character of the invention, and the manner in which its several possible embodiments meet the requirements of economical production at the rolling mill and of efficient service in reinforced structures, will be best understood upon consideration of the following detailed description, taken in connection with the accompanying drawing, and the scope of the invention will be

particularly pointed out in the appended claims.

In said drawing, Figures 1-6; Figs. 7-17; Fig. 18; Fig. 19, and Figs. 20-22, respectively, illustrate five different embodiments of my invention. Fig. 1 is a perspective view of a bar having two sets of ribs; Figs. 2 and 3 are side and bottom views, respectively, of the same; Fig. 4 is a development of its surface, and Figs. 5 and 6 are sections taken on planes indicated by line 5-5 of Fig. 2 and line 6-6 of Fig. 3, respectively. Fig. 7 is a perspective view of practically the same bar after being twisted; Fig. 8 is an elevation of the same; Figs. 9 to 16 inclusive are sections taken on planes indicated by the lines 9-9, 10-10, etc., to 16-16 respectively, of Fig. 8; and Fig. 17 is a development of its surface. Figs. 18, 19 and 20 are similar developments of bars having modified arrangements of ribs, Fig. 18 illustrating two sets of oppositely inclined ribs on each side of the bar, Fig. 19, two sets of intersecting oppositely inclined ribs on each side of the bar, and Fig. 20, one set of ribs on each side of the bar, each rib overlapping its adjacent rib by half its length; and Figs. 21 and 22 are sections of the bar having the development represented by Fig. 20, taken respectively on planes indicated by the lines 21-21 and 22-22 of Fig. 20.

Throughout these views like characters refer to like parts.

In the form of the invention illustrated in Figs. 1 to 6, inclusive, the bar A is provided with a body f of oval cross-section and two sets of ribs g and h. These ribs are oblique to the axis of the bar and preferably spirally arranged upon the lines of parallel helices, having an axis common with that of the bar, as Fig. 4 clearly shows. One set of ribs occupies the top of the body f and the other set the bottom. Each rib varies in cross-sectional area from a maximum at its center, at the top or bottom of the bar, to a minimum at its ends, at the sides of the bar. In the present instance, the section of each rib is approximately triangular in form; and as it decreases in area, the height and width of the section are gradually decreased. Obviously, the ribs might be given any other desired form of cross-section and the decrease in area might be otherwise secured.

In the form of the invention illustrated in Figs. 7 to 17, inclusive, the bar B is pro-

vided with a body *i* corresponding in cross-section to the body *f* of bar A, but having more pronounced edges, *j* and *k* at its sides. It is provided with ribs *l* and *m*, similar to the ribs *g* and *h* of bar A. In making this bar, it is first rolled into the form of bar A, except for the slightly different section of its body, and is then twisted in a direction opposite to the direction of the ribs *l* and *m*.

Obviously, this twist of the bar may be of any desired degree, but is preferably sufficient to balance the angularity of the ribs *l* and *m* and thus equalize any tendency of the bar to twist when under stress in the structure in which it is used. It is obvious that the exterior surfaces of the body portion of the bar, due to the non-circular cross-section of this portion and its twist, constitute bearing surfaces which tend to resist the longitudinal movement of the bar through the concrete or other enveloping material. The bar A is not balanced in this way, but obviously might be rendered so by twisting it as bar B is twisted. The bar A may be used in places where the tendency to turn under stress is of little or no importance, or is not produced by the stresses of the structure, such as shear stresses.

In the form of the invention illustrated in Fig. 18, the bar C is provided with a body *n* having a cross-section, like bar B, but provided with a set of ribs *o* and *p* on its top and a set *q* and *r* on its bottom, the ribs *o* and *p* being equally and oppositely inclined to the axis of the bar on the one side, and the ribs *q* and *r* being similarly inclined thereto on the other side. This bar C is not twisted and need not be, since the balancing function is provided by the equally and oppositely inclined ribs.

In each of the bars A, B and C, the cross-sections are uniform at all points, the area of the body remaining the same from point to point, and the sum of the areas of the ribs at each section being a constant. Thus, in the case of the bar A, the area cut from the body *f* by a plane at right angles to the axis of the bar will always be the same; and the sum of the areas cut thereby from ribs *g* and *h* will always be the same, but the relative areas cut from the ribs *g* and *h* will vary from point to point, as will be apparent from an inspection of the drawing. The same relation exists in the cases of bars B and C. In the three bars, the upper ribs, designated *g*, *l*, *o* and *p*, are formed in the mill by the upper roll of a pair of horizontal rolls; and the lower ribs, designated *h*, *m*, *q*, and *r*, are formed by the lower roll of such pair. In order then, for the sum of the cross-sectional areas of the ribs (when cut by a plane at right angles to the axis of the bar) to be constant, it is necessary to register the grooves in the pair of rolls by which the ribs are formed. To avoid the necessity of thus registering the rolls of the mill, I may arrange the ribs so that the sum of the areas of the ribs formed by each roll will be a constant. Thus in the form of the invention illustrated in Fig. 19, the ribs of the bar D are so arranged that the sum of the cross-sectional areas of the upper ribs *t* and *u* (formed by the upper roll) is constant and the sum of the cross-sectional areas of the lower ribs *v* and *w* (formed by the lower roll) is likewise constant, for all right sections of the bar. The intersection of *t* with *u* and of *v* with *w* are slightly widened to maintain the uniform area of the ribs at all sections. As clearly shown, the ribs *t* and *u* on the top of the bar intersect near their opposite ends and overlap each other in the longitudinal direction of the bar far enough to bring the end of each rib in transverse line with the center of the adjacent one. The same is true of the ribs *v* and *w* on the under side of the bar. In this instance, the body *s* has the same cross-section as bar B, although it is obvious that the form of the section may be varied without departing from my invention. In this bar, as in its predecessors, the ribs have the same individual cross-section and diminishing dimensions as the ribs of bar A, but obviously, these too might equally well be varied. From what has been said, it will be at once apparent that no matter where a right section of the bar is taken, the sum of the cut areas of ribs *t* and *u* will be the same, and the sum of the cut areas of ribs *v* and *w* will remain unchanged. Therefore, since each set of ribs gives a constant aggregate area, it is immaterial what positional relation they bear to each other and hence the rolls of the mill by which they are formed need not be registered, but may occupy any relative position without affecting this result. In this bar, as in bar C, the balance is provided by the equally and oppositely inclined ribs of each set, ribs *t* and *u* on the upper side, and *v* and *w* on the lower.

Fig. 20 illustrates bar E having another arrangement of ribs which obviates the necessity of registering the rolls when rolling the bar. In this instance the body *x* is provided with one set of top ribs *y* and one set of bottom ribs *z* and each rib overlaps its neighbor in the same set by half its length. In this way, the sum of the cut areas of each set of ribs remains constant from point to point and consequently registration of the rolls is not required. This bar may be twisted the same as bar B in order to balance the twist of the body against the ribs. Figs. 21 and 22 illustrate the section of the body of bar E but obviously such section might be varied to suit given requirements in a variety of ways.

From the above, it will be seen that in all forms of the invention, the ribs are small,

- regular and evenly distributed over the body of the bar. As a result, they may be formed in the last pass of the rolling mill and without heavy reductions. This avoids the difficulty of getting two sets of rolls to work accurately with reference to the ribs, as would be necessary were heavy reductions required; it enables the bar to be formed without an excessive temperature in the roughing passes and with a continued working in the neighborhood of the critical temperature (700° to 800° C.), thus producing a finer grain in the steel with a correspondingly greater strength to the bar; and the rolling of the steel at a low temperature leaves the bar practically free from scale and enables it to be rolled more accurately and uniformly as to size, with the resulting economy of material.
- 5 The oblique arrangement of the ribs enables them to be rolled easier than transverse ribs and practically as easy as longitudinal ribs. In forming the oblique ribs, the metal has only to flow upward, downward and forward. The ready flow of the metal is also facilitated by the uniform cross-sectional area of the bar.
- 10 It is well recognized that in rolling irregular bars in horizontal mills from round bars, and square bars rolled in V-shaped grooves, depressions and projections can be more easily and accurately formed at the top and bottom of the bar than at its sides, by reason of the more direct application of pressure by the rolls to the top and bottom of the bar as it passes between them. I have therefore arranged the ribs in my bars with a maximum projection and cross-sectional area at their centers, and gradually diminish both 15 to a minimum at the sides of the bar. Although a matter of minor importance, it may be noted that this form of rib thus tends to reduce the cost of production of the bar by reason of the reduced work performed by the mill in producing it. By it I also obtain practically all the advantages of a bar having a continuous spiral rib without the excessive cost and difficulties attendant upon its production.
- 20 Bars constructed according to my invention are of equal volume and practically equal exposed area per unit length, and consequently are of practically uniform temperature as they enter the last pass of the mill. This gives the finished bar uniformity of 25 texture, strength, hardness, ductility and elasticity, and hence an equal elongation per unit length when under strain. The forms of bar, which I have devised, also admit of the economical production of accurate rolls which in turn give an economical bar. These rolls may be of chilled cast-iron, or 30 steel castings, turned in the usual manner, and then grooved by means of a simple and readily obtainable revolving tool, such as a
- 35 cutter commonly used in milling machines or gear cutters. Rolls which may be thus readily machined and grooved, not only may be readily and cheaply manufactured, but also produce a uniform and economical product. Another feature of economy in the production of my bars consists in the ease of changing the mill from standard bars, such as rounds, squares, hexagons, octagons, ovals, etc., to my bar, and vice 40 versa, since in either case it is only necessary to change the rolls of the last pass. Consequently, a minimum of time is consumed in shut-downs and changes. My bars may be readily produced from any of these standard shapes by working them through the proper rolls in the last pass of the mill. In addition to these several economies of production possible in the rolling of bars constructed according to my invention, there are certain 45 structural features which especially contribute to their efficiency and utility in concrete and other reinforced structures. Thus the bar, in its several forms, is free from large flat surfaces which tend to destroy the mass effect of the reinforced structure, and which, when placed near the surface of reinforced concrete structures, are liable to cause the adjacent concrete to spall. It is also free of sharp corners and long sharp edges 50 which tend to split the concrete. By reason of the arrangement of the ribs, alone or combined with the twist of the bar, the tendency of the bar to twist in the finished structure is avoided. Furthermore, all pockets and 55 depressions in the finished bar are of such size and form that the pouring of the concrete about the bar during construction will drive out the contained air and completely fill them, thus obtaining the maximum available adhesion. The shape of the bar in its 60 several forms is also such that the centers of gravity of all right sections of the bar lie in a practically straight line coincident with the axis of the bar, and consequently the 65 elongation of the bar will be in direct ratio to the load it carries, and local stresses due to the tendency of the bar to straighten will be avoided. The shape and arrangement of the projections and depressions of the bar, by which bond with the concrete or other 70 material is provided, also increases the tensile strength of the bar, since at all right sections the combined areas of the body and ribs are the same.
- 75 Although I have employed the term "concrete reinforcing bar", it will be apparent that the bar may be employed in structures made up of other materials than concrete.
- 80 In practising my invention, obviously other shapes and arrangements of projections and depressions may be formed in the bar without departing from the spirit and scope of my invention. I therefore do not 85 wish to be limited to the specific forms here-

in disclosed, but aim to cover by the terms of the appended claims all such alterations and modifications of the same as will ordinarily occur to persons skilled in this art.

5. What I claim as new and desire to secure by Letters Patent of the United States is:—

1. A concrete reinforcing bar having a plane surfaced central body and substantially parallel isolated ribs projecting from 10 said body and extending diagonally across one face of the bar in a general spiral direction, each rib varying regularly in cross-sectional area from a maximum near the middle of the rib to a minimum at its ends and there merging into said body.

2. A concrete reinforcing bar having a plane surfaced central body of substantially oval cross-section, the relatively flat sides of the oval lying at the top and bottom of the 20 bar, and substantially parallel isolated ribs projecting from the upper and lower faces of said body and extending in each instance diagonally across one face of the bar in a general spiral direction, each rib varying 25 regularly in cross-sectional area from a maximum near the middle of the rib to a minimum at its ends and there merging into the sides of said body.

3. A concrete reinforcing bar having sets 30 of bearing faces tending to resist the longitudinal movement of the bar through the concrete, one of said sets comprising shoulders formed by the twisting of the bar, and the other of said sets being the sides of substantially parallel isolated ribs projecting 35 from the bar and extending diagonally across one face of the bar in a general spiral direction, each rib varying regularly in cross-sectional area from a maximum 40 near the middle of the rib to a minimum at its ends and there merging into the bar.

4. A concrete reinforcing bar having sets 45 of bearing faces tending to resist the longitudinal movement of the bar through the concrete, one of said sets comprising shoulders formed by the twisting of the bar, and

the other of said sets being the sides of substantially parallel isolated ribs projecting from the bar and extending diagonally across one face of the bar in a general spiral 50 direction, each rib varying regularly in cross-sectional area from a maximum near the middle of the rib to a minimum at its ends and there merging into the bar, and the spirality of the ribs being equal and opposite to the twist of the bar.

5. A concrete reinforcing bar having a set of bearing faces tending to resist the longitudinal movement of the bar through the concrete, said set being the sides of substantially parallel ribs isolated from each other and extending diagonally across one face of the bar in a general spiral direction, each rib varying regularly in cross-sectional area from a maximum near the middle of the 65 rib to a minimum at its ends and there merging into the bar.

6. A reinforcing bar of any cross-section having along its length a group of obliquely positioned projections; a second group of 70 obliquely positioned projections staggered in relation to those of the first group; the projections of one group overlapping at each end adjacent projections of the other group; successive projections of the groups 75 being relatively proportioned and arranged to provide uniform cross-sectional area of projecting material throughout the length of the bar; each said projection being wholly isolated and surrounded by the normal surface of the bar separating the same from adjacent projections, and lying entirely at one side of an axial plane of the bar whereby the surface of the bar intersected by said axial plane remains substantially unde- 80 formed.

In witness whereof, I hereunto subscribe my name this 20th day of May, 1908.

WILLIAM C. CORYELL.
